RICHARD W. RIDLEY AND ANDREW R. CLARK, OF DALLAS, TEXAS.

KITCHEN-CABINET.

No. 911,169.

Specification of Letters Patent.

Patented Feb. 2, 1909.

Application filed October 11, 1907. Serial No. 396,930.

To all whom it may concern:

Be it known that we, RICHARD W. RIDLEY and ANDREW R. CLARK, citizens of the United States, residing at Dallas, in the county of Dallas and State of Texas, have invented certain new and useful Improvements in Kitchen-Cabinets, of which the following is a specification.

Our invention relates to new and useful 10 improvements in kitchen cabinets.

The object of the invention is to provide a cabinet constructed and arranged to afford a number of compartments and receptacles in a comparatively limited space and easy of 15 access, combined with a sink, sifters and other desirable accessories.

A still further feature lies in the arrangement of the several parts in a labor saving and practical manner.

Finally the object of the invention is to provide a cabinet of the character described that will be strong, durable and efficient, comparatively simple and inexpensive to construct, and one in which the several parts 25 will not be liable to get out of working order.

With the above and other objects in view, the invention has particular relation to certain novel features, an example of which is described in the specification and illustrated 30 in the accompanying drawings, wherein:

Figure 1 is a front elevation of the cabinet, a portion of the lower drawers being broken away, Fig. 2 is a transverse vertical sectional view taken on the line $x-x$ of Fig. 1, Fig. 3 is a plan view, parts being broken away to show underlying constructions, Fig. 4 is a 35 partial vertical section showing one of the bins tilted forward, and Fig. 5 is a partial transverse vertical sectional view showing 40 the pipe connections to the sink.

In the drawings the numeral 1 designates the cabinet which is formed of any suitable material. At the upper central portion of the cabinet a compartment 2 closed by suitable doors 3 is formed. This compartment 45 may be used as a china closet or for other storing purposes. At each side of the compartment 2 flour or meal bins 4 are arranged. The fronts of these bins are formed with glass 50 panels 5 through which the amount of flour or meal in each bin may be observed. Each

of these bins is provided with a hopper bottom 6 in which a forwardly movable cut-off valve 7 is arranged to be moved by a handle 8 projecting beyond the front wall of the bin. 55 The cut-off valve 7 is placed at one side of the center of the bin so as to be over a sifter hopper 9 having a glass front 10 as shown in Fig. 1. This hopper 9 is mounted to slide outward on a horizontal support 11 in which 60 a cut-off slide 12 is mounted below the hopper. In the bottom of the hopper a wire netting 14 is arranged as a screen or sifter while a wire agitator 15 is slidably mounted on the netting and provided with a handle 16 projecting beyond the front of the hopper for manipulating the agitator. By sliding the valve 7 forward the flour or meal in the bin 4 will pass into the hopper 9 until the desired amount has accumulated when the 70 valve may be closed, the valve 12 below the hopper having of course been closed. Below the hopper a shelf 17 extends the entire length of the cabinet and on this shelf a suitable receptacle to receive the flour or meal 75 is placed. Upon sliding the slide 12 rearwardly and working the agitator 15 back and forth the flour or meal is sifted through the netting 14 into the receptacle.

At the outer side of each hopper 9 a suitable drawer 18 arranged to receive spice boxes or the like is mounted to slide and above each of these drawers small drawers 19 as indicated in Fig. 1 are arranged. Beneath the compartment 2 a plurality of 80 small drawers 20 are arranged between the bins 4 while beneath these drawers and between the hoppers 9 a plurality of bins 21 are disposed as shown in Fig. 1. Each of these bins 21 is provided with a glass front 22 85 through which the contents may be observed. Each bin is also formed with a hopper bottom 23. In this hopper bottom a slide valve 24 provided with a handle 25 projecting beyond the front of the bin, is mounted. Beneath the valve 24 a forwardly inclined spout 25 is secured to the bottom of the bin, so that when the valve is opened the contents of the bin will be directed into a receptacle placed on the shelf 17 there beneath. 95 The bins 21 are supported at their forward ends on a horizontal rod 26 and each bin is. 100

provided with a hook 27 which holds it in position when tilted forward as shown in Fig. 4. On the lower rear end of each bin a stop 28 is arranged to engage a strip 29 to support the bin when the same is tilted inward, while a pivoted stop 30 carried at upper rear side engages a facing strip 31 to limit the outward swing of the bin. By swinging this stop down, the bin may be 10 swung outward and lifted from the rod 26 when it is desired to remove or clean the same.

The lower part of the cabinet is somewhat deeper than the upper part and comprises 15 end walls 32, a back wall 33, a bottom wall 34 and a top 35 on which the upper part of the cabinet rests. This top is cut out as shown in Figs. 2 and 3 to receive a cover 36 slidably mounted so as to be moved back 20 under the shelf 17 as shown in Fig. 2 or slid forward to provide a flat working surface. This cover carries at its forward central side a ring latch 37 adapted to engage a hook 38 embedded in the front rail of the top 35 as 25 shown in Fig. 3. At the central portion a sink 39 is arranged between vertical transverse partitions 40 and provided with upwardly inclined wings 41 above which horizontal drain racks 42 are placed. It is obvious that by moving the cover 36 forward the 30 sink and drain racks are covered and a continuous surface or top provided.

At each side of the rear of the sink water supply pipes 43 as shown in Fig. 3 are provided. Each of these pipes has connection 35 with a valve 44 connected with a supply pipe 45 as shown in Fig. 5. The stem 46 of each valve extends along the end of the sink projecting through the facing strips 47 at the 40 front of the cabinet as shown in Fig. 1, so that the supply of water may thus be controlled. The sink is also provided with suitable waste and overflow pipes 48.

Beneath the wings 41 of the sink 39 drawers 45 49 are arranged. Beneath these drawers working boards 50 provided with handles 51 are slidably supported. A center board 52 is mounted beneath the sink and also provided with a handle 51. By means of these 50 handles any one of the boards may be pulled out and used or entirely removed and placed on the top 35 as is desired. That part of the cabinet lying beneath the boards 50 and between the partitions 40 and the end wall 32 55 constitute compartments 53 closed by suitable doors 54. In each of these compartments a tray 55 having a roller 56 at its rear end is arranged. The said tray is supported at its forward end on one or more rollers 57 60 mounted on the bottom 34 as shown in Fig.

2. When the door 54 is opened the tray 55 may be readily pulled out thus making it unnecessary to stoop and reach into either of

the compartments 53 to gain access to the contents thereof.

65

Beneath the center board 52 and between the partitions 40 a horizontal drawer 58 is mounted while beneath this drawer two vertical drawers 59 are arranged. On the back of the upper part of the cabinet, opposed 70 guide strips 60 as shown in Fig. 2 are secured. Between these strips vertical racks 61 are arranged to slide so as to be pulled out at each side of the cabinet as shown in Fig. 1. These racks are provided with a plurality of 75 hooks 62 upon which pots and pans and other receptacles may be hung. When it is not desired to use the racks they may be slid back of the cabinet and concealed.

It is obvious that a cabinet constructed in 80 the manner herein set forth will be extremely useful and save much time and labor to those employing it. It is constructed with a view to economy in space yet providing sufficient room and compartments for all articles used 85 in the kitchen, besides affording ample room for storing vegetables and other edibles.

What we claim, is:

1. In a kitchen cabinet, the combination with a frame work, of an upper central compartment, a closure for said compartment, a receptacle arranged at each side of the compartment, a plurality of horizontally disposed tilting bins arranged immediately beneath the compartment, and hoppers disposed beneath the receptacles to receive the 90 contents of the same, said hoppers being arranged at each end of the tilting bins. 95

2. In a kitchen cabinet, the combination with a frame work, of an upper central compartment, a closure for said compartment, a receptacle arranged at each side of the compartment, a plurality of horizontally disposed tilting bins arranged immediately beneath the compartment, hoppers disposed 100 beneath the receptacles to receive the contents of the same, said hoppers being arranged at each end of the tilting bins, a sink supported below the bins, and a movable cover for said sink. 110

3. In a kitchen cabinet, the combination with a frame work, of a sink, bins arranged above the sink, drawers arranged above the bins, a compartment above the drawers, receptacles at each side of the compartment, hoppers below the receptacles, drawers at 115 each side of the hoppers, working boards slidably mounted beneath the sink, compartments also arranged beneath the sink, trays movably mounted in said compartments, 120 closures for said compartments, and drawers arranged below the sink adjacent the said compartments.

4. In a kitchen cabinet, the combination with a frame work and upper receptacles, of 125 a sink, a movable cover for said sink, drawers

associated with the sink, working boards slidably mounted beneath the sink, vertical drawers mounted beneath the sink, compartments, one arranged at each side of the vertical drawers, a tray movably mounted in each compartment, and a closure for each compartment separate from the tray.

In testimony whereof we have signed our

names to this specification in the presence of two subscribing witnesses.
